FRACTIONATING COLUMN

Erwin C. Handwerk, Lehighton, Pa., assignor to American Metal Climax, Inc., New York, N.Y., a corporation of New York

Filed Feb. 7, 1957, Ser. No. 638,849

8 Claims. (Cl. 261—110)

This invention relates to the purification of metallic vapors and more particularly to apparatus adapted for the fractional distillation of zinc to effect its separation from contaminants such as iron, lead and cadmium.

In 1935 fourteen U.S. Patents, Nos. 1,994,345 to 1,994,358, inclusive, were granted for zinc distillation and apparatus therefor. While the production of refined zinc based on fractional distillation has spread worldwide and increased substantially in tonnage over the years, the technology of refining metallic zinc by fractional distillation has remained essentially unchanged. The technical literature discloses that the trays of fractionating columns for refining zinc, commonly made of silicon carbide, are subject to thermal strains caused by fluctuations or changes in operating conditions which may even result in completely boiling away the liquid on the trays. Such "dry" boiling along with chemical attack of the column by iron or other contaminants in the zinc undergoing purification lead to column failures resulting in excessive maintenance and interruption of operation. Yet in spite of such difficulties, no U.S. patent has issued in over 20 years which sets forth an improvement of such columns.

The conventional practice has been to form the zinc distillation column by stacking a multiplicity of trays, each having side walls for the dual purpose of confining a pool of molten metal on the tray and of supporting the stacked trays in spaced relationship to one another. This type of structure is shown in the 1935 patents, e.g., Figures 1 and 2 of U.S. Patent 1,994,349; when it is remembered that each tray is made of a refractory material, it will be readily appreciated that the trays in the lower portion of the column are particularly subject to cracking and like mechanical failures because of the substantial superimposed load and because of thermal shock due to "dry" boiling. Obviously, each failure is costly because of not only the long shut-down time required to cool and reheat the column but also the considerable labor necessary to rebuild practically the entire column to replace a damaged tray in the lower portion thereof.

In lieu of these pan-shaped trays, U.S. Patent 1,994,349 also proposes the use of saucer plates (Figures 4 and 5) which are again stacked upon one another and supported in spaced relationship by pins dependent from the lower side of each saucer plate. This proposal has still another handicap. Since the metallic vapors rising from the column condense to a large extent on the walls of the column and it is not practical to seal the edges of each saucer plate to these walls, the condensed metal will in a large measure run down these walls, by-passing the saucer plates which are designed to promote contact between the condensed metal and the metallic vapors.

The principal objects of this invention include the provision of a fractionating column for metallic vapors which is structurally simpler and more durable, is easy to operate and maintain, and ensures good fractionating contact between the metallic vapors and the condensed metal. The objects more specifically include the provision of structural elements which permit the erection of fractionating columns of any desired capacity, which are less susceptible to failure resulting from mechanical and thermal strains, and which, even when some fail, do not necessitate immediate interruption of column operation as has been the case with prior fractionating columns.

These and other objects and advantages of the in-

2

vention will be apparent from the description which follows.

In accordance with this invention, the trays of a fractionating column for metallic vapors are individually supported by the walls of the column, the inner sides of which have horizontal grooves or slots for the dual purpose of holding edge portions of the trays and preventing the by-passing of the trays by the metal condensed on these walls. Being individually supported, the trays no longer have a load-bearing function and are free to expand and contract with temperature changes because they are loosely positioned in the supporting wall grooves. The depth of these grooves is made sufficient to provide a reasonably strong support for the trays and the full capacity of condensed metal accumulated thereon and to ensure the flow of metal condensed on the interior surfaces of the column preferentially onto the trays.

In the accompanying drawing forming a part of this specification and showing a preferred embodiment of this invention without limiting the claimed invention thereto;

Figure 1 is a vertical section of a portion of a fractionating column formed of refractory materials wherein hot vapors are contacted with liquid condensed from the vapors; and

Figure 2 is a vertical section of the same fractionating column taken through line 2—2 of Figure 1.

As shown in the drawings, the fractionating column comprises a tower 10 formed by two pairs of substantially parallel walls 11, 12 and 13, 14 arranged to provide a tower opening having a rectangular horizontal cross-section. The inner sides of walls 11, 12, 13, 14 are provided with vertically spaced horizontal grooves 15. A plurality of vertically spaced trays have edge portions fitted loosely in horizontal grooves 15 which provide the sole support for these trays.

Figure 1 shows that the tray at each level in the fractionating column consists of a pair of similar tray elements 16 or 17 of rectangular shape. Each pair of tray elements 16 disposed in the horizontal grooves 15 at one level in tower 10 abut one another along the vertical center line of tower 10, whereas the pair of tray elements 17 in each of the grooves 15 at the next lower and next higher levels in tower 10 are laterally spaced from one another and one edge portion of each tray element 17 which is parallel to the opening between the spaced elements 16 fits loosely in a horizontal groove 15. In short, pairs of tray elements 16 and 17 are alternately disposed at adjacent levels in tower 10 so that hot vapors ascending through tower 10 pass through the space between each pair of tray elements 17 and flow around each pair of tray elements 16. While the hot vapors are flowing in this zigzag pattern, liquid condensed therefrom flows along each tray element 17 toward the edge which is not fitted into a horizontal groove 15, and spills over weir 18 onto the subjacent tray element 16. In turn, liquid flows from each tray element 16 to its weir 19 where it again overflows dropping to the subjacent tray element 17. It will be noted that in the fractionating column shown in the drawing, tray elements 16 are supported in horizontal grooves 15 by only one pair of opposite edge portions, whereas tray elements 17 have three edge portions fitted loosely in horizontal grooves 15. It is well to note that because two tray elements 16 are used rather than one large tray, liquid falling on these tray elements 16 will flow more positively to both of the two weirs 19 disposed on opposite sides of these elements 16.

Not only do horizontal grooves 15 provide the sole support for all of the trays in the fractionating column but also these grooves promote the flow of liquid condensed on walls 11, 12, 13, 14 onto tray elements 16, 17. That is to say, hot vapors condensed on walls 11, 12, 13, 14 will not tend to flow down the full length of these walls

but rather will tend to drip off these walls promptly after being condensed along the upper side of horizontal grooves 15. The drops of condensed liquid fall on tray elements 16, 17 and join the liquid flowing as a shallow pool across the upper faces thereof to maintain good fractionating contact with the hot vapors. The edge portions along three sides of the rectangular shape of each tray element 16, 17 is thicker than the major portion of such tray element and a weir 18 or 19 is provided along the fourth side of each tray element 17 or 16, respectively. The thicker edge portions of each tray element 16, 17 not only promote the flow of condensed liquid away from walls 11, 12, 13, 14 so as to bring this liquid in good fractionating contact with the hot vapors, but also the thicker edge portions provide maximum strength in tray elements 16, 17 at the support points.

The fractionating column of this invention is predicated on the use of refractory materials necessitated by the high temperatures at which the column will be operated and/or by the corrosive, erosive or like action of the vapors and liquid flowing through the column. Suitable refractory materials for exposure to zinc vapors and molten metal include graphite, high grade firebrick and silicon carbide. With the best refractory materials now available, it is advisable to make the maximum dimension of tray elements not more than about 3 feet and the dimension at right angles thereto not more than about 2 feet.

In view of the fact that the joints between blocks or bricks of the refractory materials used in the erection of the tower walls are prone to leak even at moderate pressures, it is highly desirable to minimize the pressure drop or differential along the vertical dimension of the fractionating column. For this reason, it is advisable to dimension the tray at each level in the column so that it occupies from about 50% to about 80% of the opening bounded by the tower walls.

A specific example of the invention will now be described with reference to a fractionating column for distilling zinc. Referring to Figures 1 and 2, each tray element 16 measures 2 feet 9 inches in length and 1 foot 6 inch in width; each tray element 17 has the same length but is 2 feet in width. Except for the edge portions, tray elements 16, 17 are 2 inches thick. Edge portions 0.8 inch wide are 3 inches thick along the two short sides and one long side of each tray element 16, 17, the other long side having a weir 19, 18 which is 0.8 inch wide and 2.5 inches high measured from the bottom face of the tray element. For a distance of 2 inches at each end of the weir side of each tray element 16, 17, the edge portion is also 0.8 inch wide and 3 inches thick so as to prevent the flow of molten zinc from the 0.5 inch deep pools on tray elements 16, 17 against the interior surfaces of walls 13, 14.

Horizontal grooves 15 are 4 inches wide measured along the height of walls 11, 12, 13, 14. The vertical distance between the upper side of a groove 15 and the lower side of the next higher groove 15 is 4 inches. Grooves 15 are 1.5 inches deep which means that the upper sides of grooves 15 completely overhang or overlap the thick edge portions of tray elements 16, 17 with a safety margin of about 0.7 inch. Accordingly, the flow of molten zinc condensed on walls 11, 12, 13, 14 into the pools on tray elements 16, 17 is ensured.

The space between each pair of tray elements 17 is 1 foot 9 inches wide so that elements 17 close off about 68% of the horizontal cross-section of the vertical opening formed by walls 11, 12, 13, 14. Each pair of tray elements 16 occupies only about 55% of this horizontal cross-section.

Various modifications of the invention may be made, upon consideration of the foregoing disclosure, without departing from its spirit or scope. For instance, the tower may be cylindrical and be provided with tray elements in the shape of circular segments fitted loosely in horizontal grooves in the inner surface of the tower. Obviously,

more than two tray elements may be used at each level particularly in large towers and the arrangement of these tray elements may follow several different patterns designed to promote good contact between vapors and liquid. Accordingly, only such limitations should be imposed on the invention as are set forth in the appended claims.

What is claimed is:

1. A fractionating column for metallic vapors formed of refractory materials, wherein hot metallic vapors are contacted with liquid metal condensed from said vapors, and flowing on vertically spaced trays in said column, which comprises a column formed by vapor-tight solid refractory walls, vertically spaced horizontal grooves formed in the inner sides of said solid walls of said column and a plurality of vertically spaced trays arranged with the edge portions of said trays fitted loosely and movably in said grooves to provide the sole support for said trays, each of said trays comprising a plurality of similar tray elements disposed loosely and movably with respect to one another in said grooves providing the sole support for each said tray.
2. The fractionating column of claim 1 wherein at least one pair of the tray elements at one level in said column abut one another while at least one pair of the tray elements in each of the next lower and next higher levels in said column are laterally spaced from one another.
3. The fractionating column of claim 1 wherein edge portions of each tray are thicker than the major portion of that tray so that a pool of liquid may be retained on said major portion of that tray by said edge portions.
4. The fractionating column of claim 3 wherein the upper side of each horizontal groove completely overlaps the thicker edge portions of the tray fitted loosely and movably in that groove.
5. An improved fractionating column for metallic vapors formed of refractory materials, wherein hot metallic vapors are contacted with liquid metal condensed from said vapors and flowing on vertically spaced trays in said column, which comprises two pairs of substantially parallel vapor-tight solid refractory walls arranged to provide a tower with an opening having a rectangular horizontal cross-section, vertically spaced horizontal grooves formed in the inner sides of at least one pair of said walls, a rectangular tray with one pair of opposite edge portions fitted loosely and movably in said grooves at each vertically spaced level in said tower to provide the sole support for said tray, and a weir along one edge portion of each said tray at right angles to said pair of edge portions fitted loosely and movably in said grooves, each said tray comprising a plurality of similar tray elements of rectangular shape disposed loosely and movably with respect to one another in said grooves providing the sole support for each said tray.
6. The fractionating column of claim 5 wherein each tray occupies from about 50% to about 80% of the opening in the tower.
7. The fractionating column of claim 5 wherein each tray element has edge portions along three sides of said rectangular shape which are thicker than the major portion of each said tray element.
8. The fractionating column of claim 7 wherein the upper side of each horizontal groove completely overlaps the thicker edge portions of the tray elements fitted loosely and movably in that groove.
